United States Patent Office

Des. 180,846
Patented Aug. 20, 1957

180,846

AIRCRAFT

Andrew Rocco, El Segundo, Calif.

Application February 16, 1956, Serial No. 40,184

Term of patent 14 years

(Cl. D71—1)

Fig. 1

Fig. 2

Fig. 3

Fig. 4

Figure 1 is a perspective view of an aircraft, showing my new design;
Figure 2 is a front elevational view thereof;
Figure 3 is a rear elevational view thereof;
Figure 4 is a side elevational view thereof;
Figure 5 is a top plan view thereof; and
Figure 6 is a bottom plan view of the same.
I claim:
The ornamental design for an aircraft, as shown.
